G. W. TYLER

WINDOW CLEANING DEVICE

Filed June 27, 1923

Patented July 1, 1924.

1,499,563

UNITED STATES PATENT OFFICE.

GEORGE W. TYLER, OF WASHINGTON, DISTRICT OF COLUMBIA.

WINDOW-CLEANING DEVICE.

Application filed June 27, 1923. Serial No. 648,056.

To all whom it may concern:

Be it known that I, GEORGE W. TYLER, a citizen of the United States, and residing in Washington, D. C., have invented new and useful Improvements in Window-Cleaning Devices, of which the following is a specification.

An object of this invention is a window cleaning device adapted for cleaning all windows, large and small both inside and outside and particularly the outside of all slidable windows irrespective of the height from the ground.

A further object of this invention is a window cleaning device of a portable character which is light and easy of manipulation and which can be used without danger to either the operator or to passers by.

A still further object of this invention is a window cleaning device which is of simple construction and which can be manufactured at a comparatively low cost.

Other objects and advantages will be apparent from the following specification and drawings which form a part hereof and in which Fig. 1 is a perspective view of a portion of a window and the cleaning device in position to clean the outside of the upper sash which is shown in lowered position.

Fig. 2 is a side elevational view of the cleaning device shown in position for cleaning the outside of the lower sash, the two sashes being shown in section.

Fig. 3 is a perspective view of a portion of the device in partly disassembled relation.

Fig. 4 is a side elevational view of a modified form of handle member.

Fig. 5 is a transverse sectional view of a modified form of wiper member which may be used in place of that shown in the previously described figures; and

Fig. 6 is a perspective view of the wiper member partially enclosed in a pad separated by a moisture proof layer.

Referring to the drawings the numeral 1 designates a handle which is substantially U-shaped with one arm considerably longer than the other, the handle being preferably made of a single piece of light tubing of brass, aluminum, or galvanized iron, it being preferable that the cheapest material be used so long as it will submit to the bending operations necessary in the manufacture

of the handle, lightness of material also being highly desirable.

The object of the U-shaped handle is that it may be positioned with the bend crossing the sash either above or below and with one arm on the inside and the other on the outside as shown in Figs. 1 and 2. The end of the longer arm is externally threaded as indicated by the numeral 2 for a purpose to be later described.

The numeral 3 designates a socket member which is internally threaded at one end as designated at 4 in order that the socket member may be connected with the shorter arm of the handle, which shorter end is externally threaded for co-operation with the threads 4.

The end of the socket member opposite the threaded end is cut on a curve as shown in Figs. 2 and 3 thus forming a flat projection or lug 5, the said projection being deflected toward the longitudinal axis of the socket member as is clearly shown in Figures 2 and 3.

Co-operating with the lug 5 is a two part clamp designated by the character W, the parts being designated at 6 and 7 respectively.

The clamp parts 6 and 7 are in plan substantially of the same shape, each comprising a perforated lug 8 and a gradually widened gripping member 9 as clearly shown in Fig. 1.

The clamp part 6 in edge elevation is slightly bent as at 10 and is provided with a substantially right angled extension 11.

The clamp part 7 in edge elevation is bent outwardly from the lug 8 as at 12 and is then twice bent inwardly as shown in Figs. 2 and 3 terminating in an extension 13.

It will be noted from the above description and particularly Fig. 2 of the drawing that the clamp parts are so formed that the wiper member, to be later described, when in clamped position, assumes an angular position relative to the socket member 3, in other words, when completely assembled the clamp extends angularly in one direction while the wiper member extends angularly in an opposite direction.

The object of the angularly related parts as above described is that the clamp will more securely hold the wiper when same is subjected to a pull in the direction of the socket member and further that the wiper

member will contact with the glass without contact of the clamp therewith.

The wiper member which is adapted to be clamped between the gripping members 9 and securely held in position by the extensions 11 and 13 consists of two members 14 and 15 respectively.

The member 14 is a core which is made of wood, rubber or other desired material and 10 may be of any desired length, and width, depending mainly upon the size of windows to be cleaned.

The member 15 is rolled about the core 14 and 15 may consist of any desirable material that is well adapted to cleaning.

The object of the threads 2 on the longer arm of the handle is that the socket member 3 may be removed from the shorter arm and secured to the longer arm when it is 20 desired to clean at a height difficult to reach with the shorter end.

The socket member 3 may be removed from the handle and be used as a handle itself especially for wiping the inside of 25 the windows.

The clamp member is pivotally secured to the lug 5 by means of a bolt 16 and is held in position by the thumb nut 17.

The clamp is pivoted so that it can be 30 turned in a plane at right angles to the common plane of the arms only. It is to be noted that in use the clamp should be so adjusted that the wiper will extend upwards toward the glass with which it contacts in use as the handle is always pulled downward both in cleaning the inside and the outside, thus in Fig. 1 the clamp is turned so that the wiper in end view extends inwardly and upwardly while in Fig. 2 the clamp is reversed, 35 i. e., given a 180° turn so that the wiper in end view extends inwardly and upwardly.

In the use of the device the core is covered with a suitable wiper pad which pad is moistened in any suitable manner and the 45 core and pad constituting the wiper are then inserted in the clamp in the desired position. In cleaning the outside of both sashes, the sashes are shifted as is common when cleaning by the old and common 50 method.

In cleaning the inside of both sashes the clamp should be removed and placed on the outside of the lug 8 in order that the wiper will in end view extend upward toward the sash and the socket member may be secured to the longer arm of the handle to clean 55 the upper sash.

In Fig. 4 is disclosed a modified form of

handle which consists of three parts, 18, 19 and 20 respectively, the parts 18 and 20 60 are straight pieces, the piece 20 being considerably longer than the piece 18, the pieces 18 and 20 being detachably connected with the U-shaped member 19 which member 19 is internally threaded at its ends and engages external threads on the adjacent ends of members 18 and 20. The modified form of handle in side view is of the same form as disclosed in Figures 1 and 2.

In the modified form of handle either 70 member 18 or 20 may be used as a handle itself, such, for example, in cleaning the inside of the window.

In Fig. 5 is disclosed a modified form 75 of wiper member in which the core 14' is circular in cross section and the pad or wiper 15' is wrapped about the core 14', the object of this form being that the pad may be rotated about the core to expose clean surfaces to the window to be cleaned. 80

In Fig. 6 is disclosed the wiper member of the previous figures, viz, core 14 and moistened pad 15. After having cleaned one or more windows it may be desirable to dry them or even to wipe others with a dry pad 85 and this is accomplished by placing a dry pad 21, over the moistened pad 15 and interposing between the pads 15 and 21 a moisture proof pad of oil cloth, rubber or other similar material as indicated at 22. The 90 edges of the pad 21 are brought together and secured by safety pins or other suitable means.

Having described specific embodiments of 95 my invention it is to be understood that I do not limit myself thereto but reserve the right to all modifications which fall within the scope of the subjoined claim.

What I claim is:—

A window cleaning device comprising a 100 U-shaped member, one of the arms of which is substantially one half the length of the other arm thereof, and a wiper holder having a socket adapted to be detachably mounted on the end of either arm of said member; 105 the proportions of parts being such that the entire interior surface of a closed window may be cleaned with the wiper when attached to the long arm, and the entire exterior surface of a window may be cleaned 110 only by reaching over the top to clean a half section and around the bottom to clean that half section with the wiper attached to the short arm.

In testimony whereof I affix my signature.
GEORGE W. TYLER.
